UNITED STATES PATENT OFFICE

STEPHEN J. BACHARDY, OF ALLENTOWN, PENNSYLVANIA, ASSIGNOR TO KWICWAY
MONEY CHANGER CORPORATION OF DELAWARE

MONEY DELIVERING MACHINE

Application filed February 3, 1930. Serial No. 425,472.

The present invention appertains to change making or money delivering machines, more particularly to the key set type, and is a division in part of the copending application, 5 Serial No. 214,062, filed August 19, 1927, in the name of James Kiss and Stephen J. Bachardy, the subject matter herein claimed being the sole invention of applicant and disclosed but not claimed in the above identified 10 prior joint application of applicant and James Kiss.

The invention involves special means for effecting coin delivery in conjunction with a selector unit and a simplified form of key holding means and release means therefor. It is particularly adaptable to that type of change making apparatus adapted to be inserted in the drawer unit of cash registers and the like and consists of a base plate upon 15 which is mounted a removable coin magazine unit, a removable selector unit including the manually operable keys and the locking means for holding the keys in depressed position. The plate also carries a depressible 20 pivoted coin chute or tray at the front portion thereof and a bar member which is actuated by downward movement of the tray to eject the desired coins from the coin magazine. Release means are provided for the 25 key locking means to automatically release the keys during the coin ejection movement of the bars.

Other and further objects and advantages of the invention will be hereinafter set forth 30 and the novel features thereof defined by the appended claims.

In the accompanying drawings:

Fig. 1 is a plan view of a cash register drawer having my invention applied thereto, certain parts being broken away;

Fig. 2 is an enlarged horizontal section of a portion of the mechanism shown in Fig. 1 taken just above the base plate and looking upwardly;

Fig. 3 is a side elevation of the money paying or change making unit as shown in Fig. 1, but removed from the drawer;

Fig. 4 is an enlarged section on line 4-4 of Fig. 3; and

Fig. 5 is a section on line 5-5 of Fig. 4.

Like reference characters designate corresponding parts throughout the several figures of the drawings.

Referring to the drawings in general, the arrangement of the mechanism which enters 55 into the construction of these improvements is similar to that of the prior Patent No. 1, 223,354, and it is to be understood here that while the exemplification of the invention is shown in conjunction with a cash register 60 drawer, it is not entirely confined to this field. Preferably, however, the mechanism is mounted in the forepart of the cash register drawer A which forms an adjunct to the conventional cash register provided with the 65 usual register keys, the operation of which releases the drawer in the customary manner.

The mechanism of this invention comprises the removable coin magazine unit X, removable selector unit Y and the ejector actuating 70 mechanism Z. The first of these units will now be described.

The removable coin magazine unit consists of the coin magazine or holder in the form of a casting having a suitable number of 75 coin receptacles 1 for holding the various denominations of coins making up the component parts of a dollar. These open front receptacles are covered by a panel of glass 2 through which the contents may be always 80 seen when the drawer is closed, and they are also partly closed at the bottom by a plate 3, and bottom of the tray 30.

Slidably mounted upon this plate beneath the coin receptacles are the respective ejectors 85 5. These ejectors each have a coin receiving opening 6 and spaced spring receiving slots 8 provided with springs 9 which hold the ejectors in retracted position with the opening 6 beneath the particular coin receptacle. 90 This unit slips easily into place in the front portion of the drawer, resting on the bottom 10, and is held by set screws 11 at each side mounted in lugs 12 formed to overhang the side extensions 13 of the unit with which the 95 set screws engage.

The selector unit which is also detachably secured just in rear of the coin magazine unit is composed of the side frame members 14 which support the transverse holding frame 100

15, slotted to receive the key selector members 16 shown in detail in Fig. 4. The vertical key extension 16a of each member 16 is slotted at 16b to receive a spring 17. The bar proper 16c is notched as usual for clearance of the actuators therebeneath which are not to be operated by this bar and each bar is provided with an end extension 16d cooperating with a latch plate 18 located at the respective ends of the frame 15. It is to be understood that there is one of these plates at each end of the frame and that the selector bars of one half of the keyboard have their extensions 16d cooperating with one of these plates and the other half with the other of said plates, thereby providing a flexible keyboard. Each of the plates 18 is formed with off-standing ears 19 having apertures to receive the pivot screws 20 connecting the plate to the end frame member. The lower end of the plate is formed with an extension finger 21 (as clearly seen in Fig. 4) which is disposed centrally of the lower edge so as not to interfere with the engagement of the selector bars beneath said edge when said bars are depressed.

A spring 22 bears against the upper end of the plate and normally holds it in contact with the end of the frame at a point beneath the pivot. It will be seen that this plate at the lower edge is bent inwardly as indicated at 18' so as to provide a camming surface with which the above mentioned end of the selector bar coacts when moving downwardly to rock the plate about its pivotal axis. When the tip of the bar passes below the plane of the lower edge, the plate snaps back into place and retains the bar in the lowered position until it is released by the operation of the actuator mechanism, as hereinafter explained, or by the operation of a second key. A simple form of selector unit is thereby provided.

The actuator mechanism or unit comprises the cross bar 23 slidably mounted over an opening 24 in the bottom of the drawer and said bar has fixed thereto the longitudinal bars 25 guided at opposite sides by guides 26. Springs 27 are provided, normally holding the unit at its rearmost position. The cross bar is notched to receive a plurality of ejector actuators 28, pivotally secured to the pintle rod 29 carried by said bar. These actuators extend forwardly beneath the selector bars to a point just in rear of the coin ejectors, their free ends being held elevated normally by springs 29a so as to be inoperative with relation to the ejectors until depressed into the plane of the latter. When so depressed by the proper selector bar, the ejecting operation will take place upon movement of the bar in a forward direction relative to the drawer. To the forward edge of the bottom of the drawer is hingedly connected a coin chute or tray 30 having side extensions 31

connected by side bars 32 to the ends of the cross bar 23. This chute extends across the front of the coin magazine unit and normally remains in horizontal position under the influence of the springs 27, said chute being adapted to catch the coins which are moved by the ejectors 5 in the ejecting operation. 70

By swinging the chute downwardly into the dotted line position shown in Fig. 3 the actuator mechanism is pulled forwardly to 75 eject the coins selected by the proper keys, these coins sliding down to the delivery opening 33 and being caught by the hand used to manipulate the chute. Release of the chute immediately permits it to rise under the action of the springs 27 to its original position, but the same result may be automatically produced, so to speak, as an incident to the closing of the drawer. To this end, the extremity of the bar indicated at 25a, engages a 80 lug or stop on the drawer support of the cash register which may be located in the path of movement of said bar 25a of Fig. 2, the lug being engaged by the end and the bar held as the drawer is pushed home. Owing to the 85 relative movement of the drawer with respect to the actuating mechanism, the ejector function is performed as hereinbefore described.

Formed in each of the side bars 32 intermediate the ends thereof is a release cam 34, the function of which is to release the respective lock plates 18 during the forward movement of the actuating mechanism. Each of these cams in such forward movement is 90 brought into contact with the end of the depending finger 21 of the lock plate and the cam will shift the lock plate laterally to a sufficient degree to release the selector bars which may be retained by the locking plate 100 in a depressed position. This action is clearly shown in Fig. 4 of the drawings. 105

It is of course contemplated that the drawer when released by the register key operation will be moved outwardly under the 110 action of the usual spring (not shown) at the rear of the drawer.

While the operation of the device will be clear from the foregoing description, it is desired to give a general outline of a change 115 making operation which will take place in the use of this apparatus under proper manipulation.

Assuming that a sales transaction has been made amounting to seventy cents, the operator will press the seventy-cent cash register key or keys which will register the sale amount in the cash register and permit the drawer to move into its outward position where the change making unit becomes accessible and operable. The key of the selector unit comprising the difference between seventy cents and one dollar, or the thirty-cent key, is now depressed. This will move the proper selector bars downwardly until 120

they are engaged by the lock plates at the ends of the selector unit.

The operator may now press downwardly on the coin chute while holding his hand over the mouth of the same, such action causing the actuating mechanism to move forwardly so as to bring the depressed actuator bars into engagement with the rear ends of the proper ejectors, the twenty-five cent ejector and the nickel ejector. These ejectors shift the respective coins from the magazine receptacles forwardly until they drop through the openings onto the chute from which they slide into the operator's hand.

15 It is to be understood that when the drawer is to be automatically actuated by an abutment on the cash register the connection between the chute and the cross bar 23 may be removed, in which event the chute would hold the coins in the receiving openings until the chute is depressed by the operator. Under such conditions the chute would be provided with an actuating spring on its pintle so as to be restored to its normal position.

25 While the specific details of construction have been herein shown and described, the invention is not confined thereto as changes and alterations may be made without departing from the spirit thereof as defined by the appended claims.

Having thus described my invention what I claim as new and desire to secure by Letters Patent is:

1. In a money paying machine of the class described, a drawer, a support for the drawer, a coin magazine mounted in said drawer having coin ejectors therefor, a selector unit for controlling said ejectors including manipulating keys and selector bars, latch plates at the ends of said bars for holding the operated selector bars, actuating means for said ejectors controlled by said selector bars and release means controlled by said actuating means and engageable with said latch plates to release the same incident to actuation of the ejectors.

2. In a money paying machine, a drawer, a support therefor, a coin magazine unit associated with said drawer including coin ejectors, a selector unit for controlling operation of the ejectors and including manipulative keys and vertically movable selector bars, latch plates at the ends of said bars for holding the operated selector bars, actuating means for the selectors and release means for the latch plates, said release means being rigid with said actuating means.

3. In a money paying machine, a support, a coin magazine thereon, a selector unit including a frame, a plurality of selector bars movable within said frame, a pivoted lock plate on one end of said frame engaging said bars, actuators for ejecting coins from said magazine adapted to be depressed by said bars, a movable actuating bar carrying said

actuators, and a link transmission for operation of said actuating bearing, said link having means to release the latch plate to permit return of the selector bars.

4. In a money paying machine, a coin magazine, ejectors for ejecting coins from said magazine, an actuating unit for said ejectors comprising a movable bar, actuating members on said bar deppressible to engage said ejectors, a key set selector unit for depressing said actuating members comprising a plurality of parallel bar members provided with actuator engaging portions and notched nonengaging portions, latch plates on said unit adapted to engage the ends of said bars to hold them in depressed position, and operating means for causing ejecting movement of the actuating unit and simultaneous release movement of the latch plates.

5. In a money paying machine, a coin magazine, ejectors therefor, a selector unit comprising a frame, selector bars carried by the frame mounted for vertical movement, actuating elements for the bars, each of said bars being provided with a cam face and latching shoulder substantially in the plane thereof, a latching mechanism for holding said selector bars in depressed position including a resiliently mounted plate adapted to be actuated by the cam portion of the bars and engageable with the shoulder, and actuating means for the ejectors adapted to actuate the latching plate to release the depressed bars.

6. In a money paying machine, a frame, a coin ejecting mechanism, selector bars deppressible in said frame to engage the coin ejecting mechanism, means normally holding the bars in nonengaging position, a latch member carried by the frame and arranged when depressed to engage the ends of the bars to hold them in engagement with the coin ejecting mechanism, means for actuating the coin ejecting mechanism, said means having a cam conformation rigid therewith to trip said latch member.

7. In a selector unit for money paying machines, a frame, selector bars vertically movable within the frame and provided with cam and shoulder extensions, a latch plate engageable with said shoulder extensions when the bars are depressed, and means for effecting coin discharge for tripping the latch plate.

8. In a money paying machine, a selector mechanism comprising a support, a plurality of movable selector bars carried by the support terminating in a cam extension and shoulder, a latch plate carried by the support and engageable with one of said shoulders when a plate is depressed to hold the same, and actuating means to operate the ejectors and actuate the latch plate to release the selector bars.

9. A selector unit for money paying ma-

chines comprising a frame, parallel selector bars vertically movable with respect to said frame, each of said bars terminating in a cam face and shoulder portion, springs for holding the bars elevated, latching means carried by the frame for engaging the shoulders of the bars when depressed to prevent return thereof, and a cam member engageable with said latching means to cause said latching means to release the depressed bars.

10. In a money paying machine having a coin magazine and associated coin ejectors, actuators therefor, a frame, a plurality of notched shiftable selector bars having manipulating keys therefor to depress the bars into engagement with certain parts of said actuators, latch means carried by the frame shiftable to maintain one of said bars depressed and provided with an extension, and means to operate said actuators, said means having a cam conformation engageable with the extension on the latch to cause simultaneous release of the depressed bars and movement of the actuators.

11. In a money paying machine of the class described, a coin magazine having coin ejectors therefor, a selector unit for controlling said ejectors including manipulating keys and selector bars, latch plates for holding the operated selector bars and located at the ends of said bars, and actuating means for said ejectors controlled by said selector bars, hand-controlled operating means for said actuating means, release means carried by said operating means and engageable with said latch plates to release the same incident to actuation of the ejectors.

12. In a money paying machine, a drawer, a support therefor, a coin magazine unit associated with said drawer including coin-ejectors, a selector unit for controlling operation of the ejectors and including manipulative keys and vertically movable selector bars, lock plates at the opposite ends of said bars and cooperative therewith for holding the operated selector bars, actuating means for the ejectors, release means for the lock plates, said release means carried by said actuating means.

13. In a money paying machine, a drawer, a support therefor, a coin magazine unit associated with said drawer including coin

ejectors, a selector unit for controlling operation of the ejectors and including manipulative keys and selector bars, lock plates at the ends of said bars for holding the operated selector bars, actuating means for the ejectors, release means for the lock plates, said release means constituting special conformations of said actuating means.

14. In a money paying machine, a support, a plurality of coin ejectors, a selector unit controlling the operation of said ejectors including a frame, a plurality of selector bars movable within the frame, a pivoted lock plate on one end of said frame engaging said selector bars, actuators for causing said ejectors to eject coins from said magazine adapted to be actuated by said selector bars, a movable actuating bar carrying said actuators, and a link connection between said chute and said actuating bar, said link having a portion coacting with the latch plate to permit return of the selector bars.

15. In a money paying machine, a support, a coin magazine thereon, a selector unit including a frame, a plurality of selector bars movable within said frame, a pivoted lock plate on one end of said frame engaging said bars, actuators for ejecting coins from said magazine adapted to be actuated by said bars, a movable actuating bar carrying said actuators, and a link transmission for operating said actuating bar, said link being correlated with the latch plate to release the latter in order to permit return of the selector bars.

16. In a money paying machine, a coin magazine, ejectors for ejecting coins from said magazine, an actuating unit for said ejectors comprising a movable bar, actuating members on said bar depressible to engage said ejectors, a key set selector unit for depressing said actuating members comprising a plurality of parallel bar members provided with actuator engaging portions and notched non-engaging portions, latch plates on said unit adapted to engage the ends of said bars to hold them in depressed position, and operating means for causing ejecting movement of the actuating unit and simultaneous release movement of the latch plates.

In testimony whereof I affix my signature.
STEPHEN J. BACHARDY.
